The ornamental design for a panel cap for a display panel, as shown and described.

DESCRIPTION

FIG. 1 is an isometric view of the invention;
FIG. 2 is a front elevational view of the design shown in FIG. 1;
FIG. 3 is a rear elevational view of the design shown in FIG. 1;
FIG. 4 is a side elevational view of the design shown in FIG. 1;
FIG. 5 is a top plan view of the design shown in FIG. 1; and
FIG. 6 is a bottom plan view of the design shown in FIG. 1.
